UNITED STATES PATENT OFFICE

2,588,316

HOPPER BOTTOM LOAD DISCHARGING CAR

Albert E. Zimmer, Chicago, Ill., assignor to Enterprise Railway Equipment Company, Chicago, Ill., a corporation of Illinois

Application April 8, 1948, Serial No. 19,805

4 Claims. (Cl. 105—292)

1

This invention relates to hopper bottom load discharging cars, more especially to a type suitable for economical track ballasting service, and the like, and has for an object the provision of new and improved mechanisms for operating the drop doors thereof.

Another object of the invention is to provide winding mechanisms which employ sprocket link chains, for supporting drop doors, of much greater strength and simplicity than the coil chains commonly used for this purpose, and which enable me to reduce the number of chains for supporting a set of doors.

Another object of the invention is to provide winding mechanisms wherein sprocket wheels and sprocket chains of novel construction are employed in such manner as to keep the chains and winding mechanism in alignment at all times, and in all positions of the operating mechanism.

A further object of the invention is to provide means whereby the chains may be connected or disconnected with reference to the winding sprockets with a minimum of labor and cost.

A still further object of the invention is to provide winding mechanisms which include sprocket wheels eccentric in shape, and so mounted on the operating shaft as to provide for a minimum of torsion on the shaft and which vary the speed-force ratio, dependent upon the positions of the doors during operation thereof.

Other and further objects of the invention will appear from the specification and annexed claims, and from the accompanying drawings, in which:

Fig. 1 is a transverse sectional view of the lower portion of a hopper bottom load discharging car, showing the invention applied thereto;

Fig. 2 is an enlarged, broken, part sectional view, through a portion of the car on the line 2—2 of Fig. 1, and showing mechanism for operating the center doors;

Fig. 3 is an enlarged, broken, vertical sectional view on the line 3—3 of Fig. 2;

Fig. 4 is an enlarged, fragmentary, end elevation of the sprocket and chain mechanism employed in connection with the invention;

Fig. 5 is a fragmentary sectional view of the construction shown in Fig. 4, and corresponding substantially to the line 5—5 of Fig. 4; and

Fig. 6 is an enlarged, exploded, clinographic perspective view of the chain links employed in connection with the invention.

As shown in the drawings, the car itself may be of a conventional type, having longitudinally

2

extending hoppers 8 and 9 at opposite sides of the center sill construction 10. The hoppers 8 and 9 are each formed by oppositely inclined sheets 11 and 12, the lower marginal edges 13 of which are adapted to be contacted by the free marginal edges of longitudinally extending outer doors 14 and of the inner doors 15, both the doors 14 and 15 being pivotally supported upon hinge members 16, and adapted when fully open to rest against supports 17.

The outer doors 14 of each set of doors at opposite sides of the center sill 10, are adapted to be operated by winding mechanisms 18 and 19 disposed beneath the hopper sheets 11 at each side of the car, the mechanisms 18 and 19 being identical and description of one should suffice for both, similar reference characters being employed to designate correspondingly similar parts.

20 The winding mechanism 18 includes supporting means 20 for a winding shaft 21 adapted to carry and rotate sprocket sheaves or wheels 22. As best shown in Fig. 4, each sheave or wheel 22 comprises a body web 23 and a laterally extending peripheral rim portion 24, spirally or eccentrically disposed about a square hub 25 through which the shaft 21 extends, the center of the hub 25, and hence of the shaft 21, being indicated at 26. The effective winding surface of the peripheral rim 24 of the wheel 22, beginning adjacent to a chain attaching portion 27 of the web 23, is slightly flattened, as at 28, to provide a rest for a chain link, and there extends along a curve which progressively recedes, farther from the center 26 until it reaches its maximum distance therefrom, as indicated at 29. A plurality of sprocket teeth 30 project radially from the rim 24 at predetermined intervals, and the teeth 30 are contoured to nicely fit sprocket links of an operating chain 31.

40 The chain 31 includes a plurality of alternate links 32 and 33. Each of the links 32 is of elongated form, reduced in curved contours 34 between the ends 35, and reduced, as at 36, to lighten the construction. The ends 35 are exteriorly rounded, and each end has an aperture 37, the defining wall of which is slightly tapered in opposite directions to form seats 38. The links 33 each comprises split sections 39, which are alike, each being reduced between its ends 40, and each end provided with a laterally extending slightly tapered apertured boss 41, the bosses 41 of complementary sections of each link 33 being adapted to extend into the apertures 37 of adjacent links 32 to fit the seats 38, and adapted

to be secured in position by rivets, such as indicated at 42 in Fig. 5. The links 33 between the ends are spaced so as to receive the sprocket teeth 30 upon the wheel 22.

The end link 33 may be readily attached or detached with reference to the portion 27 of the wheel, the latter being provided with an opening 43 for the reception of one of the bosses 41 and being of a thickness substantially coinciding with the length of one boss, so that a boss 41 of a complementary link section may be shifted with respect to the securing portion 27, as shown in dotted lines in Fig. 4, once the rivet 42 is removed. This provides for ready attachment and detachment of the chain 31 with reference to the wheel 22. The opposite end of the chain 31 may be secured to the related door 14 by the usual eye bolt 44, Z-bar and angle bar arrangement 45.

For operating the center doors 15 a somewhat heavier center shaft 46 is provided, having mounted thereon sprocket wheels 47 and 48, similar to the wheel 22, except that the same are circularly instead of eccentrically formed and do not have the detachment feature. The chains 49 and 50 are similar to the chain 31 but single links, such as link 32, are affixed to the sprocket wheels 47 and 48 respectively. The chains 49 and 50 extend through openings 51 and 52 in the walls of the center sill 10, over sheaves 53, and are connected to the inner doors 15 by connections similar to those already mentioned.

To minimize possibility of fouling of the chains 49 and 50, a curved guard plate 54 is attached to the center sill 10 and overlies the wheels 47 and 48, and the chains thereon, and the guard 54 operates to prevent displacement of the chains. In the event such displacement should occur, the chains will be dropped to one side or the other of the center sill walls so as to remain suspended without damage.

It will be appreciated that upon rotation of the shafts 21 the sprocket wheels 22 will be rotated and by reason of the eccentric formation thereof a greater leverage will be applied when the doors 14 are fully open, and thereafter when the load becomes less the speed of closing movement is accelerated. The sprocket wheels and chains described afford substantially precision positioning and operation of the parts, and by reason of the chain and wheel formation the chains may be readily attached or detached with reference to the wheel. Additionally, the chains employed are of exceptional strength and consequently the number of wheels and chains necessary for efficient operation will be greatly reduced.

While I have shown and described a preferred embodiment of the invention, it will be appreciated that the same may be variously modified and changed without departing from the spirit of the invention; accordingly, it will be understood that I do not limit myself to the preferred embodiment disclosed, but consider my invention to cover all changes or modifications as come within the scope of the appended claims.

I claim:

1. A winding mechanism for operating the hopper door of a railway hopper car or the like, in combination, a rotatable shaft having a winding member thereon provided with chain attaching means; and a chain adapted to be connected

at one end to said door, said chain having split hinged sections at the opposite end adapted to embrace said attaching means, and shiftable with respect to each other to facilitate attachment and detachment; and means for fixing said hinged sections against detachment.

2. A winding mechanism for operating the hopper door of a railway hopper car or the like, in combination, a rotatable shaft having a sprocket wheel thereon with an apertured chain attaching portion, a chain adapted to be connected at one end to said door, said chain having split hinged sections at the opposite end having opposed bosses extending toward each other and adapted to embrace opposite sides of said attaching portion, the thickness of said apertured attaching portion being about the same as the length of one of said bosses whereby said one boss can project through the aperture in said portion while the other boss clears the same thereby facilitating attachment of said chain to said portion, and fastening means extending through said bosses for securing said hinged sections to said portion.

3. A winding mechanism for operating the hopper door of a railway hopper car or the like, in combination, a shaft, a drum fast on said shaft having a curved winding face, and a flexible connection extending between said shaft and door and adapted to be wound on said face of said drum, said connection being formed by a series of rigid links pivotally united together, said links being curved intermediate their pivotal connection to correspond substantially to the curvature of said winding face whereby they seat bodily on said drum and provide continuity of bearing for said flexible connection.

4. The invention, as set forth in claim 3, wherein means are provided for deflecting the connection from a straight line including a pivoted element having a curved face on which the links are arranged to bear, the curvature of said face corresponding substantially to that of said links.

ALBERT E. ZIMMER.
